(57) CLAIM

The ornamental design for a brush head for electric toothbrush, as shown and described.

DESCRIPTION

FIG. 1 illustrates a perspective view of a brush head for electric toothbrush, with stippling shading applied to some bristles to show contrast in appearance.

FIG. 2 illustrates a first side of the brush head.

FIG. 3 illustrates a second side of the brush head.

FIG. 4 illustrates a third side of the brush head.

FIG. 5 illustrates a fourth side of the brush head.

FIG. 6 is a top view of the brush head; and,

FIG. 7 is a bottom view of the brush head.

The broken lines shown in the drawings illustrate portions of the brush head for electric toothbrush that form no part of the claimed design.

1 Claim, 6 Drawing Sheets
